PUMP FOR COMPRESSED LIQUEFIED
GASES

Claude F. Tears, Mountain Lakes, N. J., assignor
to The Petroleum Processes Corporation,
Wichita, Kans., a corporation of Kansas

Application July 31, 1933, Serial No. 682,948

1 Claim. (Cl. 103—202)

In pumping compressed liquefied gases, a peculiar difficulty is created by reason of the highly volatile character of the material. The thin film of liquid which adheres to the rod of the pump piston evaporates as it reaches the air on the out stroke of the pump, causing any room moisture to freeze on the rod, producing an ice crust which impedes the back stroke of the piston rod, cuts the packing of the gland and otherwise interferes with proper operation of the pump.

The objects of this invention are to overcome the difficulties mentioned and to do so in a thoroughly practical and inexpensive way.

These objects are attained by the novel combinations and features of invention hereinafter disclosed in the specification and broadly covered in the claim.

The drawing accompanying and forming part of the specification illustrates one of the present commercial embodiments of the invention, it being understood that the structure may be modified as regards this particular illustration all within the true spirit and broad scope of the invention.

Fig. 1 of the drawing is a broken side elevation of a steam pump construction having the invention incorporated therein.

Fig. 2 is an enlarged vertical sectional detail as on line 2—2 of Fig. 1.

The pump shown comprises a steam cylinder 3, and a liquid cylinder 4, the same having pistons operating therein connected by a piston rod 5, sliding through glands 6, 7 at the confronting ends of the cylinders.

The steam cylinder may have the usual steam supply and exhaust connections, suitable supply piping being indicated at 8. The piping for the liquid or pump cylinder is not shown, the same varying with requirements.

At 9, a branch connection is indicated extending from the steam supply pipe and terminating in nozzles 10, 11, positioned to direct small jets of steam onto opposite sides of the piston rod adjacent the point of emergence from the packing gland 7.

A valve 12 is shown in the branch line for governing the amount of steam used and individually regulatable valves may be provided in the nozzle pipes 13, 14, for separately adjusting the two steam jets. These nozzle pipes are shown

as extending downwardly from the branches 15, 16, of a special U-shaped elbow 17, having a side inlet 18, in the arch of the U screwed onto the end of the supply piping 9.

The nozzles for the steam jets consist simply of inturned ends of the vertical jet pipes 13, 14, but if desired, a special nozzle or nozzles, such as for spraying steam or other frost dissipating fluid all around the pipe, may be provided.

In practice, it has been found best to locate the steam jets, so as to discharge on the packing gland as well as on the piston rod, the jet nozzles being shown located closely adjacent the packing gland for this reason.

With this invention, the film of highly volatile liquid clinging to the emerging piston rod is instantly dissipated and enough heat applied to the surface where evaporation occurs to prevent ice formation.

The structure illustrated is practical and can be inexpensively applied to existing pumps for handling liquefied gases, such as propane, butane and the like, but the invention is not restricted to this particular form of structure and modifications in form may be made to suit particular requirements or conditions. Also other medium than steam may be used. Thus, heated compressed air or other gaseous material may be used to prevent the freezing effect on the projecting piston rod. The de-frosting or frost preventive spray may be intermittent, instead of continuous, being timed for example, by an automatic valve driven by or synchronized with the pump to prevent or dissipate the frost film as the piston rod is on its out stroke or has completed the out stroke and is about to reenter the stuffing box.

What is claimed is:

In a pump for compressed liquefied gases, the combination of steam and pump cylinders with pistons operating therein connected by a piston rod operating through glands at the confronting ends of the cylinders, steam connections with the steam cylinder and piston rod steaming means supplied from said steam connections and located adjacent the gland of the pump cylinder and including a steam nozzle directed toward the piston rod connected by piping with the steam connections aforesaid, said piping having a controlling valve therein.
